UNITED STATES PATENT OFFICE.

ALFRED C. STEWART, OF PASADENA, CALIFORNIA.

THERMOSTATIC CONTROL MEANS FOR WATER HEATERS.

Application filed October 26, 1923. Serial No. 670,995.

This invention relates to automatic control of water heaters of the storage type in which a body of water in a suitable tank is maintained at an approximately constant 6 temperature by automatic control of the gas supply thereto. In an apparatus of this kind it has been usual to thermostatically control the gas supply only, with the result that when the desired temperature of the 10 water has been obtained and the gas supply is automatically shut off, cold atmospheric air continues to pass into the water heater and as it is not then warmed by combustion gas it exercises a cooling action on the heater, resulting in considerable loss of heat 15 which has to be compensated for by combustion of a correspondingly increased amount of gas.

The main object of the present invention 20 is to increase the efficiency of the water heater by cutting off or controlling the air supply simultaneously and correspondingly with the gas supply so as to prevent the heat loss above referred to and provide for maximum efficiency of the heater.

The accompanying drawings illustrate my invention.

Fig. 1 is a vertical section of a water heater provided with my improved controlling means.

Fig. 2 is a section on line 2—2 in Fig. 1.

Fig. 3 is an enlarged vertical section of the gas and air controlling means.

Fig. 4 is a corresponding section showing a modification.

The water heater shown in the drawing comprises a water container, tank, or receptacle 1 formed for example as a vertical cylinder provided with inlet means 2 for cold water and outlet means 3 for hot water and mounted in a suitable or usual manner. The tank 1 is enclosed in an outer casing 4 spaced from the tank to form a passage 13 for hot gases and provided at its upper end 40 with an outlet 5 for such gases and at its lower end with a combustion chamber 6 formed for example in a base 7 on which the tank 1 and casing 4 are supported. Said combustion chamber is provided with burner means comprising a mixing chamber having air and gas valve seats 15 and 16 at its lower end. A jacket 8 may surround the casing 4 leaving an intervening space 9 which may be packed with suitable heating insulating 45 material.

The top of combustion chamber 6 is

formed by the bottom of tank 1 and said tank is provided with an inner tube 10 extending upwardly from its bottom and opening at the lower end into the combustion 60 chamber and closed at its upper end. A bar, rod, or other thermostatic control member 12 is connected at its upper end to the tube 10 and is connected at its lower end to the valve means for controlling the supply of gas and 65 air as hereinafter described. Said tube 10 and rod 12 constitute a thermostatic unit extending vertically within tank 1 so as to be subjected to the temperature of said tank. The rod or member 12 consists of material 70 of different expansibility from that of the material of the inner tube 10, for example, said member 12 may be of iron, the inner tube being of brass, so that by reason of the greater thermal expansion coefficient of 75 brass as compared with iron an increase of temperature in the members 10 and 12 due to or accompanying an increase of temperature in the body of water in the heater tank 1 causes a relative elongation of member 10 80 and upward movement of lower end of rod 12. On the lower portion of member 12 is mounted a valve member consisting for example of a plate or disk 14 adapted to cooperate with the circular valve seats 15 and 16. 85 Valve seat 15 is formed on the bottom of a tubular member 17 extending upwardly from the bottom of the combustion chamber 6, the interior of said tubular member 17 forming the mixing chamber 11, and communicating at its lower end with the space within the base member 7 under the control of the valve disk 14, said space, indicated at 18, communicating with the outer air through an opening 19. A top member 90 formed as a plate or disk 21 extends over the tubular member 17 but is spaced therefrom by spacers such as wires 22 so as to leave a constricted annular slot 23 through which the mixed gas and air can escape into 95 the combustion chamber 6 for combustion therein. The thermostatic control rod 12 extends freely through the top plate 21 and is attached to the valve disk 14 which is adapted to close to any desired extent, the lower end of the tubular member 17, said valve disk being preferably adjustable on the control member 12 for example by screwing thereon as indicated. A gas supply duct indicated at 25 is adapted for communication 100 with the gas supply pipe indicated at 26 and communicates with a vertical pas-

sage 27 in a member 28 surrounding the control rod 12 and having the valve seat 16 at its lower end, the valve seats 15 and 16 being for example in the same plane so that a substantially flat disk 14 may cooperate with both of them simultaneously.

The combustion chamber 6 opens through passages 30 into the space 13 between the tank 1 and jacket 8.

10 Suitable means may be provided for igniting the mixture as it issues into combustion chamber 6 for example, a pilot flame pipe 32 extending from the gas duct 25 aforesaid, and opening into the combustion chamber 6 adjacent to the outlet 23 for the mixture. In order to enable access to the pilot flame, for example for ignition thereof, an opening 35 may be provided in the wall of the base 7, said opening being normally closed 20 by plug 36 (see Fig. 1).

In case it is desired to admit auxiliary air into the combustion chamber 6 for ensuring combustion of the mixture admitted thereto, suitable auxiliary air passages may be provided, controlled by thermostatic means above described so as to control the admission of such auxiliary air in correspondence with the admission of gas and mixture. For this purpose auxiliary air passages or inlets 38 may be provided communicating with the combustion chamber 6 and controlled by valve members 39 connected to the thermostatic controlling rod 12, being attached for example to the valve plate or disk 14 aforesaid, so as to move and operate simultaneously therewith to control admission of air to the auxiliary air ports 38 in correspondence with the admission of the air to the air port or passage formed within the tubular member 17.

40 The operation is as follows:

Gas being supplied to the heater by means of pipe 26 and water being supplied by means of pipe 2 so that the interior of the tank 1 is full of water and the pilot flame being ignited the operation of the burner starts by reason of the fact that when the tank 1 and contents thereof are cold the valve member 14 is depressed due to the relative contraction of the thermostatic control member 10 at this time and gas will therefore flow into the mixing chamber 11 within tubular member 17 and air will flow into such chamber from the inlet opening between the valve seat 15 and the valve member 14. The resulting mixture of combustible gas and air flows out through the outlet 23 and is ignited by the pilot flame and the resulting hot combustion gases pass out 50 through the passages 30 and upwardly in

the space 13 around the tank 1, thereby heating the water in the tank. When the tank and the contents thereof are at a sufficiently high temperature the consequent elongation of the thermostatic control member 10 causes the valve member 14 to be raised so as to close the air and gas inlets to a greater or less extent, and as the supply of air is shut off in correspondence with the supply of gas there will be no cold air flowing in contact with the tank at any time and the maximum conservation of heat is secured. In case auxiliary air is used as in the embodiment shown in Fig. 4 such auxiliary air is shut off at the same time as the mixing air so that in that case also there is no possibility of flow of cold air through the heater when the main burner is not in operation. It will be understood that the device acts as a regulating means as well as a shut off means, so that the supply of gas and air is gradually decreased as the temperature of the tank rises, and gradually increased as the temperature of the tank falls.

85 What I claim is—

1. In a water heater of the storage type, a tank for containing water, burner means provided with a mixing chamber, means for admitting gas and air to said mixing chamber, means for admitting auxiliary air to said burner means independently of said mixing chamber, a single valve member operable to control the means for admitting gas and air to the mixing chamber and also the means for admitting auxiliary air, and a thermostatically controlled member extending adjacent said tank and adapted to be heated by the water therein and connected to said valve member to control the same.

2. In a water heater of the storage type, a tank for containing water, burner means provided with a cylindrical mixing chamber, means defining an annular orifice for the admission of gas to said mixing chamber, means defining an annular orifice concentric and exterior to said first-named orifice for the admission of air to said mixing chamber, and thermostatically controlled means extending adjacent said tank so as to be subject to the temperature of the water therein and adapted to simultaneously control the size of both of said annular orifices.

110 In testimony whereof I have hereunto subscribed my name this 11th day of October 1923.

115 ALFRED C. STEWART.
